UNITED STATES PATENT OFFICE.

FREDRICK E. MCKINNIS, OF ST. JOSEPH, MISSOURI.

ATTACHMENT FOR SCREEN-DOORS.

1,184,191.

Specification of Letters Patent.

Patented May 23, 1916.

Application filed April 6, 1915. Serial No. 19,526.

To all whom it may concern:

Be it known that I, FREDRICK E. MCKINNIS, a citizen of the United States, residing at St. Joseph, in the county of Buchanan and State of Missouri, have invented certain new and useful Improvements in Attachments for Screen-Doors, of which the following is a specification.

This invention contemplates an improved 10 device especially adapted for attachment to screen doors and designed to prevent the entrance of flies or insects through the door opening when the door is either opened or closed.

15 The invention has as its primary object to provide a device of this character which will be automatically operable upon either opening or closing the door, and to also provide means for preventing flies or insects 20 from entering through the door opening from over top of the door.

25 A further object of the invention in this connection, is to provide a flapper swingingly mounted upon the free side edge of the door and to provide an operating rod for the flapper adapted to rotate the flapper as the door is either opened or closed.

30 The invention has as a still further object to provide a canopy upon the door casing and to also provide a sweep arranged to coact with the canopy for preventing flies or insects, when the door is opened, from entering through the door opening through the space above the door. And the invention 35 has as a still further object to provide an improved device which may be readily applied to any conventional type of screen door without the necessity of structural change therein and which will be simple in 40 construction and thoroughly efficient in use.

45 Other and incidental objects will appear as the description proceeds and in the drawings wherein I have illustrated the preferred embodiment of the invention and wherein 50 similar reference characters designate corresponding parts throughout the several views, Figure 1 is a front elevation showing my improved device applied to a conventional type of screen door, Fig. 2 is a sectional view taken on the line 2-2 of Fig. 1 and more particularly showing the mounting of the flapper employed, Fig. 3 is a perspective view showing the canopy detached with the parts thereof disassembled but in

proper operative position, Fig. 4 is a perspective view of the flapper detached and the operating rod therefor, and Fig. 5 is a fragmentary perspective view of the sweep carried by the door and adapted to coact with the canopy.

55 For convenience, I have, in Figs. 1 and 2 of the drawings, shown my improved device in connection with a conventional type of screen door, wherein the numeral 10 designates the door casing and the numeral 11, 60 the door, the door being provided with side rails 12 and 13 respectively, top and bottom rails 14, and an intermediate rail 15. As shown in Fig. 1 of the drawings, the door is swingingly mounted within the casing 10 by 65 suitable hinges connected to the side rail 12 of the door. Mounted upon the outer face of the side rail 13 of the door is a flapper indicated as a whole by the numeral 16 and which includes a rod or shaft 17 arranged 70 to extend longitudinally of the rail 13 substantially throughout its entire length, or in other words, substantially throughout the entire height of the door, it being observed that the said rod at one end, is bent to provide a laterally directed terminal or arm 18. Connected to the arm 18 is a clip or sleeve 75 19 which, as best shown in Fig. 4 of the drawings is preferably formed from a single strip of suitable sheet metal bent to embrace the arm with its extremities disposed in overlapping relation. Disposed between the overlapping ends of the clip 19 and secured thereto in any suitable manner is one end of a strip of wire screening 20, the opposite end of which is received between and connected to the overlapping terminals of 80 an arm 21 connected to the shaft 17 at a point intermediate its ends. As best shown 85 in Fig. 4 of the drawings, the arm 21 is also 90 preferably formed from a single piece of sheet metal bent to embrace the shaft, with its ends disposed in overlapping relation, and the arm 21 is, as will be noted, of a length substantially equal to that of the arm 18, being disposed to coact with said last 95 mentioned arm in rigidly supporting the strip of wire screening or reticulate element 100 20 upon the shaft.

105 Mounted upon the shaft 17 in longitudinal spaced relation to the arm 21 is an arm 22 substantially identical in construction with the arm 21 and mounted upon the said

shaft, contiguous to the adjacent lower terminal thereof, is a terminal arm 23 also similar to the arm 21. Extending between the arms 22 and 23 is a strip of wire screening 24 or other reticulate element, the said strip of screening being suitably secured at its ends, to the arms. The strips 20 and 24 may be made any desired width and constitute the reticulate body portion of the 10 flapper adapted to rotate with the shaft 17. Mounted upon the upper and lower rails 14 of the door are attaching brackets 25. Each of said brackets is preferably formed from a strip of suitable sheet metal 15 detachably secured at one extremity, in any suitable manner to the adjacent rail, while the opposite extremity thereof is bifurcated to form spaced lugs 26 which are bent to freely embrace the shaft 17. In this connection, it will be observed that the bracket 20 arranged at the top of the door is adapted to contact with the arm 18 of the said shaft for supporting the shaft vertically upon the door. Secured to the side rail 13 of the 25 door at points immediately upon each side of the center rail 15, are attaching brackets 27 which are also each preferably formed from a strip of suitable sheet metal having one terminal thereof detachably connected 30 to the said rail with the other terminal bent to freely embrace the shaft 17. The shaft 17 is thus rotatably supported upon the free margin of the door by the several brackets 25 and 27, with the body portion of the 35 flapper 16 of which it forms a part, adapted to seat flatly against the adjacent margin of the outer face of the rail 13 and against the adjacent outer face of the casing 10 of the door, in the manner best shown in Fig. 1 of 40 the drawing.

Formed on the shaft 17, at a point intermediate its ends and arranged between the arms 21 and 22 secured to the shaft, is a pinion 28. However, this pinion may be 45 keyed to the shaft if desired and arranged to coact therewith is a rack bar or rod 29 disposed to extend transversely of the door 11 substantially in a plane with the center rail 15 thereof as best shown in Fig. 1 of the drawings. The bar 29, at one extremity, is swingingly supported by a suitable pivot pin 30. As best shown in Fig. 4 of the 50 drawings, the pivot pin 30 is screw threaded adjacent one end thereof to detachably engage the casing 10 and is of a length to extend laterally from the casing, being bifurcated at its outer free end to form spaced ears 32 between which the adjacent 55 flat terminal 33 of the bar 29 is freely received, the said flattened terminal of the bar being connected with the said ears by a suitable pivot pin 34 as more particularly shown in Fig. 1 of the drawings.

60 The rack bar 29 is arranged to extend freely through the longitudinally spaced

guide loops 35 carried by the center rail 15 and at its free end, is provided with a rack 36 normally meshing with the pinion 28. At this point, it may be stated that the 70 guide loops 35 are preferably in the nature of staples which may be driven into the center rail 15 of the door.

It will now be seen that when the door 11 is opened, the rack bar 29 will engage the pinion 28 to rotate the shaft 17 and consequently, move the flapper 16 upon the free margin of the door in a direction away from the casing 10 and toward the outer face of the door, as the door is swung upon its 75 hinges. In this connection, particular attention is directed to the fact that such turning movement will be imparted to the flapper 16 simultaneously, as the door 11 starts to open.

The rack 36 of the bar 29 is preferably arranged to actuate the flapper 16 through an arc of substantially 90° from the normal position shown in Fig. 1 of the drawings in substantial parallel relation to the casing 10 and door 11, to a position at substantially right angles to the door. Upon reaching such last mentioned position, as the door is opened, and the swinging movement of the door is then continued, the teeth of the rack bar will be moved to a position upon one 90 side of the pinion 28 out of engagement therewith, so that the flapper 16 will stand at a position at substantially right angles to the door. When the door is then again closed, the teeth of the rack bar will, as will 100 be clear, be again brought into engagement with the pinion 28 to consequently return the flapper to normal position as the door moves to closed position.

It will thus be seen that the flapper 16 105 will be automatically operated each time the door 11 is opened or closed. The reticulate body portion comprising the elements 20 and 24 of the said flapper will, when the door is being opened and when the said body portion is being moved into angular relation to the door, be adapted to prevent or render it difficult for flies or insects to enter through the door opening and it will be observed that the construction provided is 110 very simple and may be readily applied to any conventional type of screen door without the necessity of structural change 115 therein.

120 Mounted above the door opening to extend laterally from the casing 10 is a canopy shown in detail in Fig. 3 of the drawings. This canopy is, in general contour, preferably the shape of a quadrant and includes a frame 37. As best illustrated in Fig. 3, the 125 frame 37 is formed from a single strip of suitable sheet metal bent intermediate its ends to provide side portions 38 and 39 which are joined by a longitudinally curved 30 connecting portion 40. The side portions 38

and 39 are preferably straight and the side portion 39 is provided at its free end, with a terminal lug 41 adapted to seat flatly against the adjacent free terminal of the side portion 38 to be secured thereto in any suitable manner. The frame 37 is secured to the casing 10 above the door opening in the manner shown in Fig. 2 of the drawings with the side portion 38 of the frame 10 seating flatly against the adjacent outer face of the casing and being detachably connected thereto by screws or other suitable fastening devices. Fitting over the frame is a reticulate body portion 42, preferably 15 formed of suitable wire screening and one margin of which is disposed between the side portion 38 and the casing 10 and is thus held in position. The remaining margins of the body portion are bent laterally in the 20 manner shown in Fig. 3 of the drawing, to seat against the inner faces of the side portion 39 of the frame and the connecting portion 40 thereof, and are held in position by a retaining member or band 43.

25 The band 43 may be formed of wood or any other suitable material and is adapted to fit within the adjacent angle between the side portion 39 and the connecting portion 40 of the frame to seat against the said portions. Preferably, the retaining band 43 is provided at longitudinally spaced points with a plurality of openings adapted to align with similar openings formed in the side portion 39 and the connecting portion 35 40 of the frame, the said aligned openings being disposed to receive bolts or other suitable fastening devices for detachably holding the retaining band in position in engagement with the adjacent margins of the 40 body portion.

Arranged to coat with the canopy mounted above the door opening, is a sweep 44 shown in detail in Fig. 5 of the drawings. The sweep 44 may be formed from a strip 45 of fabric heavy paper, bristles, or any other suitable material, and is preferably provided, at one margin thereof with a plurality of flexible fingers 45. The sweep 44 is secured to the upper margin of the 50 upper rail 14 of the door in any desired manner to extend longitudinally thereof substantially throughout the transverse width of the door as best shown in Fig. 1 of the drawings, with the fingers 45 extending 55 upwardly to contact with the reticulate body portion 42 of the canopy, it being observed that the connecting portion 40 of the frame of the canopy, is arranged concentric with the arcuate path traveled by 60 the outer free edge of the door in its swinging movement as the door is opened or closed. It will thus be clear that the sweep 44 will coat with the canopy to prevent flies or insects from entering through the 65 door opening from over top of the door.

Having thus described my invention, what I claim and desire to secure by Letters Patent is:—

1. A device of the character described including a rotatably mounted flapper, and an operating rod for the flapper, the said flapper being adapted for attachment to a door with the rod pivotally connected to the door casing, whereby the flapper will be rotated upon the door as the door is opened. 75

2. A device of the character described including a flapper having a rotatably mounted shaft, and an operating rod operatively engaging the shaft, the said flapper being adapted for attachment to the free longitudinal edge of a door with the said rod pivotally connected to the door casing, whereby the rod will rotate the shaft upon the opening of the door. 80

3. The combination with a swingingly mounted door, of a flapper rotatably mounted thereon, the said flapper including a shaft provided with a pinion, and an operating rod pivotally connected to the door casing and provided with a rack operatively 90 engaging said pinion whereby the flapper will be rotated when the door is opened. 85

4. In a device of the character described, a flapper including a rotatably mounted shaft, and a reticulate body portion supported by the shaft upon one side thereof to rotate with the shaft, and a rod operatively engaging the shaft, the said flapper being adapted for attachment to a door with the rod swingingly connected to the door casing, whereby the flapper will be rotated 100 when the door is opened. 95

5. The combination with a swingingly mounted door, of a flapper arranged upon the door, said flapper including a rotatably mounted shaft, arms carried by the shaft, and a reticulate body portion carried by said arms and mounted to turn with the shaft, brackets carried by the door and operatively supporting the shaft, a pinion 110 formed on the shaft, an operating rod provided with a rack operatively engaging said pinion, and a pivot pin connected to the door casing and freely supporting said rod whereby the flapper will be rotated simultaneously 115 with swinging movement imparted to the door. 105

6. The combination with a swingingly mounted door, of a flapper including a shaft rotatably mounted upon the door, a pinion carried by the shaft, and an operating rod swingingly connected to the door casing and provided with a rack normally engaging said pinion, whereby the flapper will be rotated when the door is opened, the rack 120 being disposed to disengage the pinion at a point in the opening movement of the door. 125

7. The combination with a swingingly mounted door, of a rotatably mounted flapper carried by the door, means for ro- 130

tating the flapper simultaneously with the swinging movement of the door, a canopy supported by the door casing, and a sweep carried by the door and adapted to coact with the canopy.

8. A device of the character described including a freely mounted flapper, and operating means therefor, said flapper being adapted for attachment to a door with the said means operatively fixed at a point adjacent the door to move therewith whereby the flapper will be shifted upon the movement of the door.

9. A device of the character described including a freely mounted flapper, and operating means for the flapper, the flapper being adapted for attachment to a door with the said means operatively fixed at a point

adjacent the door whereby the flapper will be shifted upon the movement of the door, 20 said means being adapted to disengage the flapper at a point in the opening movement of the door.

10. The combination with a door, of a freely mounted flapper carrier thereby, and 25 means operatively fixed at a point adjacent the door for automatically shifting the flapper upon the opening or closing movement of the door.

In testimony whereof I affix my signature 30 in presence of two witnesses.
